UNITED STATES PATENT OFFICE.

SAM SORENSEN, OF HOUSTON, TEXAS, ASSIGNOR TO J. H. GIESSEY, OF HOUSTON, TEXAS.

ROTARY DRILL.

Application filed July 1, 1928. Serial No. 119,943.

- This invention relates to rock drill bit structures and it consists in the novel arrangements of its parts and features as hereinafter described and claimed.
- Under prevailing practices it is customary to assemble mating sections or halves in the form of a bit body, and these sections are screwed into the end of a drill collar when the body is applied thereto. It has been found to be practically impossible to positively hold the body sections immovable with relation to each other and the body fixed with relation to the collar. Slight relative movements incident to impact and vibration occur, and such movements cause the threads to strip and stick into the drill collar so that it is almost impossible to remove or separate the parts. Welding hard bronze and other metals into the drill collar and then threading the same has been resorted to for the purpose of correcting or preventing such objections but this expedient is objectionable, expansive and generally unsatisfactory.
- At intervals it is necessary to remove the bit body from the collar, either by breaking out or unscrewing, and then separating the sections of the body in order to renew worn reamers or cutters. With the present invention it is unnecessary to detach the body from the collar when it is desired to renew the reamers and cutters. However should it be necessary to remove the body from the collar, this may be readily accomplished by unscrewing, in that the convolutions of the threads of the body and collar are continuous from end to end and are not made up of originally aligned sections which may shift or move with relation to each other.
- Another object of the invention is to render the cutters and reamer elements readily accessible for purposes of repair or replacement, and to that end the invention contemplates a novel manner of constructing the body whereby a movable member thereof may be utilized to carry one of the cutters as well as to cooperate with the main part of the body for holding the reamer elements in convenient detachable relation thereto.
- A further feature of the invention resides in a novel construction for mounting the conical shaped cutters at the lower end of the body, as well as for supplying a lubricant to the bearings thereof.
- A still further feature of the invention resides in the provision of novel means for mounting and retaining the side reamers in the body.
- With the above and other objects in view which will more readily appear as the nature of the invention is better understood, the same consists in the novel construction, combination and arrangement of parts herein-after more fully described, illustrated and claimed.
- A preferred and practical embodiment of the invention is shown in the accompanying drawings, in which:
- Figure 1 is a side elevation of the drill bit structure showing the parts thereof in relative closed position and with the drill collar shown in section.
- Figure 2 is a view similar to that shown in Figure 1 and looking at a side of structure at a right angle to that shown in Figure 1.
- Figure 3 is a side elevation of the structure showing the parts thereof in relative open position.
- Figure 4 shows an enlarged fragmentary view of a drill bit partly in section, and
- Figure 5 shows an enlarged fragmentary cross sectional view thereof taken on the line 5—5 of Figure 4.
- As illustrated in the accompanying drawing the collar 1 is of usual form and is provided at its end with an internal thread 2. The drill bit structure is attached to the said collar and the thread thereof as will herein-after be described.
- The bit structure includes a body member 3 provided at its upper cone shaped end with a thread 4. The convolutions of the thread 4 are continuous from end to end of the thread and the thread 4 is adapted to engage in the thread 2 of the collar when the body member is applied thereto. The body member is provided at its side with a longitudinally extending recess 5 which leads in from that end of the body member opposite the end thereof which is threaded. The upper end wall surface of the recess 5 is located between the ends of the body member and is arcuately curved as at 6. The body member is provided with a lug 7 which fits in the recess 5 at the end thereof and which joins with the curved wall 6. The body member is provided at a point between the ends of the recess with a chamber

8 which partially receives reamers 9 of conventional form. A cutter 10 is journaled at the lower end of the body member.

The bit structure also includes a swinging body section 11 adapted to nest or fit in the recess 5 of the body member. The section 11 is bifurcated at its upper end and is provided with arcuate end surfaces 12 which bear against the arcuate surface 6 defining the end 10 wall of the recess in the body member. Bolts 13 pass transversely through the body member and the body section and carry pins 14. Said bolts and pins serve to hold the body section in a closed position in the recess 5 as 15 best shown in Figure 1. The body section 11 is pivotally connected with the lug 7 by means of a pivot pin 15 which passes transversely through the bifurcated end of the section and the lug.

20 The structural arrangement is such that the thread 4 cannot strip or stick in the thread 2. Therefore the body may be readily detached from the drill collar. The bolts 13 may be withdrawn from the body member 25 and the body section 11, and the section may be swung to an open position with relation to the body member as shown in Figure 3 of the drawing, and hence the reamers and cutters may be renewed without detaching the 30 bit structure from the collar. The engaging arcuate end surfaces of the recess 5 and the body section 11 permit the section to swing with relation to the body member and at the same time any thrust strain applied to the 35 pivoted section 11 when open or closed is transmitted to the body member 3 along said arcuate surface, thus relieving the pivot pin of such strain. Also the lug 7 being located at the end of the recess 5 and joining with the arcuate end wall thereof adds rigidity to 40 the structure and holds the pivoted section 11 in proper registry wth the body member 3 and the receiving recess 5 therein. This relieves the bolts 13 of torsional strain when 45 the tool is being used for drilling in rock or other hard or dense material.

It is to be noted that the lower ends of the body members 3 and 11 have the diverging lower end faces 16, 16, thus providing a trans- 50 verse pocket in which the cutters work, the bases, or large ends of said cutters, being disposed toward said faces 16, 16 and formed integrally with said respective diverging faces 16 are the inwardly and downwardly 55 converging bearing pins 17, which taper slightly toward their free ends and fitted over each pin there is a thimble like washer 18, each washer having an annular flange 19 which is bolted to the corresponding face 16 by means of suitable set bolts as 20 and these 60 washers take the wear incident to the rotation of the cutters 10, protecting the body members against such wear, and these washers, when worn, may be readily removed and re- 65 placed.

There is a diagonal bore 21 through each of the members 3 and 11 which extend axially through the pins 17 and which are reduced forming internal annular shoulders 22. Bearing bolts 23 are provided whose inner 70 ends 24 are reduced and threaded into the corresponding cutters 10 and by their reduction there are formed thereon external annular shoulders 25 which abut the opposite part of the corresponding cutters 10. The 75 outer end of each bearing bolt has an enlarged head 26 which abuts the corresponding shoulder 22 and thus retains the corresponding cutter on the pin 17, the shoulder 25 preventing said bearing bolt 23 from being screwed up too tight so that the cutter 10 will not have too close a fit on the washer 18 surrounding the pin 17. The bearing bolt 23 may be equipped with a bushing 27 formed of brass, or other suitable material. The 80 outer end of the bore 21 may be filled with a lubricant which is retained therein by means of a suitable plug, as 28, screwed into the outer end of said bore and this lubricant finds its way into the bearing of the bolt 23 as 85 well as of the cutter 10.

There is a novel type of side reamer, shown in Figures 4 and 5, which is also mounted in a novel manner. This reamer is designated by the numeral 29 and is located in the side 95 recess of the body, one on each side. The reamer is cylindrical in general contour and has an axial bearing on the bearing pin 30, the upper and lower ends of this pin having the transverse keys 31, 31, therethrough, 100 whose ends project into sockets as 32 in the abutting face of the body member 3 and the section 11 respectively, so as to hold the pin 30 against rotation. During the operation of the bit in drilling the pressure on the reamers 29 will be inwardly so that the outer side of the pin 30 will take the wear and when this side of the pin has become worn the pin may be readily turned half-way around and 105 will then serve the purpose, practically, of a new pin.

While the essential features of the invention have been herein described, it will be understood that minor changes in the form, proportion and details of the various parts of the construction may be resorted to without departing from the spirit or sacrificing any of the advantages of the invention.

I claim:

1. A drill bit for earth boring operations 120 comprising a body member having an integral collar engaging portion at one end and a side recess, a body section pivotally connected to the body at one end of the recess and adapted to lie flushly therein, and said body and said recess being provided with complementary chamber forming portions, a reamer mounted in said chamber forming portions, means for locking the body section and body together at a point remote from their point of 125 130

pivotal connection, and cutters carried by the lower end of both the body section and body.

2. A drill bit for earth boring operations comprising a body consisting of two sections having their meeting faces located substantially in the plane of the axis of the bit, one of said sections being provided with an integral collar attaching portion, means for holding said sections together, and said sections of the body being provided with complementary chamber forming recesses, a reamer element adapted to be removably fitted in the chamber formed by said recesses, and cutters carried by both of said body sections.

3. A drill bit structure for earth boring operations comprising a main cutter carrying body and a movable cutter carrying section pivoted to the cutter carrying body on an axis at right angles to the bit axis, said body end section having complementary chamber forming portions in their meeting faces, reamers mounted in said chamber forming

portions, and means for locking said cutter carrying section and body together adjacent their earth engaging ends.

4. A drill bit structure for earth boring operations comprising a main body member having an integral collar attaching portion at one end, a cutter carried by the other end, and a movable section pivoted adjacent the collar engaging portion and adapted to swing toward and away from the main body member, a cutter carried by the lower end of said movable section, and said main body portion and said movable section having complementary chamber forming portions at their meeting faces, reamers removably mounted in said chamber forming portions, and means for locking the movable section and main body together, adjacent the cutter carrying ends thereof.

In testimony whereof I hereunto affix my signature.

SAM SORENSEN.
